[57] CLAIM

The ornamental design for a truck security storage box, as shown and described.

DESCRIPTION

FIG. 1 is a perspective view of the truck security storage box of the instant invention with the lid open;

FIG. 2 is an enlarged top view of the truck security storage box of the instant invention with the lid shown in closed position;

FIG. 3 is a bottom view of the truck security storage box of FIG. 2;

FIG. 4 is a perspective view of the truck security storage box of the instant invention with the lid closed;

FIG. 5 is one end view of the truck security storage box of FIG. 4. The opposite end view is the mirror image;

FIG. 6 is an enlarged front elevation view of the truck security storage box of FIG. 4; and,

FIG. 7 is an enlarged rear elevation view of the truck security storage box of FIG. 4.

The portions of the interior of the storage box which are not visible in FIG. 1 form no part of the claimed design.
